CORD REEL FOR STAND LAMPS

Christopher Richard Stocks, Sacramento, Calif.

Application August 10, 1937, Serial No. 158,340

8 Claims. (Cl. 242—107)

This invention relates generally to floor or bridge lamps and in particular is directed to a cord reel adapted for use in combination with a lamp of such type. I am aware that cord reels for floor lamps have heretofore been known but such prior devices have been, in most instances, complicated in structure and expensive to manufacture. Further, they did not provide the desired ease of operation; that is the cord reel spring was of such type and so mounted that when a substantial length of cord was drawn from the reel, the torque was excessive.

The principal objects of my invention are to provide a cord reel for floor lamps which is simple in construction, inexpensive to manufacture, and one which operates smoothly and effectively regardless of the amount of cord withdrawn from the reel.

Another object of my invention is to provide a cord reel assembly arranged for mounting as a unit in the base portion of a floor lamp, the assembly being easily removable for replacement or repair if necessary.

These objects I accomplish by means of such structure and relative arrangement of parts as will fully appear by a perusal of the following specification and claims.

The figure on the drawing is a sectional elevation of my improved cord reel assembly as mounted in connection with the base portion of a floor lamp.

Referring now more particularly to the characters of reference on the drawing, the numeral 1 indicates the base of a floor lamp, such base being hollow and provided with an upstanding sleeve 2 in which is seated the lower end of the vertical tubular standard 3 of the lamp as is usual.

A relatively large cord reel or drum 4 is disposed horizontally within the hollow base 1 and is formed integral with a vertical spindle 5 which extends upward through sleeve 2 and into the lower portion of the tubular standard 3. The reel 4 and spindle 5 are preferably made of dielectric material such as "bakelite". The spindle 5 is hollow and communicates at its lower end with a central, downwardly opening cavity 6 in the drum. The drum is formed with a relatively deep cord receiving groove 7 and a passage 8 leads from cavity 6 to the bottom of groove 7.

The lower portion of dielectric spindle 5 is provided with a metallic sleeve 9 surrounding the same in fixed connection, the lower end of this sleeve being preferably molded into the upper surface of reel 4 as at 10. The metallic sleeve

9 is threaded at its upper end to receive an adjustment nut 11 which also serves as a thrust bearing as will hereinafter appear. The nut 11 is locked to sleeve 9 by means of a set screw 12. The nut 11 rests on the upper end of a bushing 13 through which the spindle 5 and sleeve 9 turnably project, the latter having a running fit in the bushing. The bushing is secured within sleeve 2 by means of an integral flange 14 which extends beneath the flat portion of the base. This flange is held in place by screws 15, mounted from below, an opening 16 in the reel affording access to the heads of such screws from beneath the lamp base.

A tubular housing 17 surrounds the upper portion of the bushing and extends upward some distance within standard 3 and surrounding spindle 5. A collar 18 is fixed in the upper end of housing 17 and serves as the bearing for the upper end of spindle 5. A set screw 19 holds the housing 17 in place on bushing 13 while a set screw 20 maintains collar 18 in place.

A relatively long, helical wound torque spring 21 of small pitch surrounds spindle 5 within housing 17, one end of this spring being connected with nut 11 while the other end is connected with collar 18. This spring is made of relatively light spring wire which gives the spring an exceedingly small torque action for each revolution of the spindle and reel and which will permit of a substantial number of revolutions of reel 4, without excessive spring resistance being set up.

When in use, my improved cord reel assembly is mounted in connection with a floor lamp in the manner hereinbefore described and a relatively light and flexible electric cord C extends from the globe sockets of the lamp within skirt 3 and is threaded through spindle 5 into cavity 6. From cavity 6 the cord extends through passage 8 and is then wound about the reel 4 in groove 7 a number of times, the outer or free end of the cord being passed through an opening O in one side of the base. This opening may be provided with a suitable grommet if desired. Of course such outer or free end of the cord is provided with the usual two-prong plug adapted to engage in an electric outlet socket.

When it is desired to connect the lamp cord C with an electric outlet socket the necessary amount of cord is unreeled from reel 4. When this occurs spindle 5 rotates and places spring 21 under torque. As the spring 21 is relatively long and of light torque, a considerable amount of the cord may be taken from the reel without

increasing the torque excessively and the cord leading to the outlet socket will normally be held under light tension. Also when not in use the cord will run back onto the reel easily and without snapping back. It is necessary with my construction that the cord C be quite light and flexible in order that it may run back onto the reel under the influence of the light torque spring 21.

If for any reason it is necessary to remove the 10 cord reel assembly from the lamp as for repair or replacement, the screws 15 need only be removed and the entire assembly can then be withdrawn.

From the foregoing description it will be readily 15 seen that I have produced such a device as substantially fulfills the objects of the invention as set forth herein.

While this specification sets forth in detail the present and preferred construction of the device, 20 still in practice such deviations from such detail may be resorted to as do not form a departure from the spirit of the invention, as defined by the appended claims.

Having thus described my invention, what I 25 claim as new and useful and desire to secure by Letters Patent is:

1. A cord reel assembly for a lamp having a hollow base and a tubular standard, said assembly comprising a reel adapted to be disposed horizontally 30 within the hollow base of the lamp, a vertical spindle projecting upward from the reel and adapted to extend into the tubular lamp standard, means to secure the spindle against longitudinal movement without restricting the rotation thereof, a helical torque spring surrounding the spindle, and means connecting the spring at one end with the spindle and at the other end with the standard; said last named means comprising a non-turnable bushing mounted within the 35 standard, about the spindle, and a thrust element surrounding the spindle and fixed thereon, said element engaging the upper end of the bushing.

2. A cord reel assembly for a lamp having a hollow base and a tubular standard, said assembly 40 comprising a reel adapted to be disposed horizontally within the hollow base of the lamp, a vertical spindle projecting upward from the reel and adapted to extend into the tubular lamp standard, a bushing surrounding the lower portion of the spindle, means to secure the bushing within the standard, a thrust element on the spindle and engaging the upper end of the bushing, a bearing collar surrounding the upper end portion of the spindle, means to secure the collar in connection 45 with the standard, and a helical torque spring surrounding the spindle between the thrust element and collar, the adjacent ends of the spring being secured to said element and collar respectively.

3. A device as in claim 2 in which the spindle 50 includes a unitary and surrounding sleeve extending through and projecting beyond the upper end of the bushing, the projecting portion of said sleeve being threaded; said thrust element comprising a nut on the threaded portion of the sleeve.

4. A cord reel assembly for a lamp having a hollow base and a tubular standard, said assembly 55 comprising a reel adapted to be disposed horizontally within the hollow base of the lamp, a vertical spindle projecting upward from the reel and adapted to extend into the tubular lamp standard, a bushing surrounding the lower portion of the spindle, a flange extending outwardly from 60 the lower end of the bushing and adapted to en-

gage the under surface of the base, mounting screws extending through the flange from beneath, the reel having an opening therein to afford access to said screws, a thrust element on the spindle and engaging the upper end of the bushing, and a helical torque spring surrounding the spindle, said spring being connected at one end with the thrust element and at the other end with the standard.

5. A cord reel assembly for a lamp having a 10 hollow base and a tubular standard, said assembly comprising a reel adapted to be disposed horizontally within the hollow base of the lamp, a vertical spindle projecting upward from the reel and adapted to extend into the tubular lamp stand- 15 ard, a bushing surrounding the lower portion of the spindle, means to secure the bushing within the standard, a thrust element on the spindle and engaging the upper end of the bushing, a bearing collar surrounding the upper end portion of the 20 spindle, a housing within the tubular standard and surrounding the spindle in clearance relation, said collar being mounted within the upper portion of the housing, the lower portion of the housing being secured in connection with the 25 bushing, and a helical torque spring surrounding the spindle between the thrust element and collar and secured at adjacent ends thereto.

6. A cord reel assembly for a lamp having a hollow base and a tubular standard comprising 30 a cord reel adapted to be disposed in the base, a tubular spindle upstanding from the reel to project into the standard and through which the cord passes to the reel, a bushing about and engaging the spindle immediately above the reel, a thrust 35 element rigid with the spindle above and riding on top of the bushing, a spring mounted in connection with the spindle and bushing and acting to yieldably resist rotation of the spindle in one direction, and means removably mounting the 40 bushing in the base.

7. A cord reel assembly for a lamp having a hollow base and a tubular standard comprising a cord reel adapted to be disposed in the base, a tubular spindle upstanding from the reel to project into the standard and through which the cord passes to the reel, a bushing about and engaging the spindle immediately above the reel, a thrust element rigid with the spindle above and riding on top of the bushing, a spring mounted in connection with the spindle and bushing and acting to yieldably resist rotation of the spindle in one direction, a flange on the bushing engaging the under face of the base about the standard, and removable screws securing the flange against the 55 base.

8. A cord reel assembly for a lamp having a hollow base and a tubular standard comprising a cord reel adapted to be disposed in the base, a tubular spindle upstanding from the reel to project into the standard and through which the cord passes to the reel, a bushing about and engaging the spindle immediately above the reel, a thrust element rigid with the spindle above and riding on top of the bushing, a spring mounted in 60 connection with the spindle and bushing and acting to yieldably resist rotation of the spindle in one direction, a flange on the bushing disposed between said base and the reel, and screws securing the flange against the base and inserted from 65 below; the reel having an opening therethrough to register with the screws one at a time to render the same accessible for removal without first removing the reel.
